UNITED STATES PATENT OFFICE.

LOUIS F. RUZIECKI, OF LOS ANGELES, CALIFORNIA.

COMBINATION CARPENTER MACHINE.

Application filed February 23, 1923. Serial No. 620,689.

To all whom it may concern:

Be it known that I, LOUIS F. RUZIECKI, a citizen of the United States, residing at Los Angeles, in the county of Los Angeles 5 and State of California, have invented certain new and useful Improvements in Combination Carpenter Machines, of which the following is a specification.

My invention relates to woodworking machinery, and the objects are first, to construct an interchangeable tool for sawing, planing, boring, turning, grinding, etc.; second, to provide a machine for carpenters, cabinet makers, pattern makers, and unskilled workers, that is easy to operate and quickly changed from one operation to another.

Another object is to provide a combination carpenter machine that is simple in construction and inexpensive to operate.

Other and still further objects and advantages will appear from the following description taken in connection with the accompanying drawings forming a part of this specification and will be pointed out in the claims.

Referring to the drawings Figure 1 represents a side elevation of my combination carpenter machine.

Figure 2 represents a plan view of Figure 1, with the top table removed.

Figure 3 represents a sectional view on line 3—3 of Figure 2.

Figure 4 represents a fragmentary view 35 of a grinding attachment for Figure 3.

Figure 5 represents a fragmentary view of a drilling attachment for Figure 3.

Figure 6 represents a fragmentary view of a turning attachment for Figure 1.

Figure 7 represents a section on line 7—7 of Figure 2.

Again referring to the drawings in which like characters of reference designate similar parts, the bed 1 comprises the entire lower stationary structure of the machine, the sides 26 are secured to the bed 1 from one end-portion thereof and extend longitudinally with the said bed 1, towards the opposite end-portion thereof to a predetermined 45 point, the carriage 2 is operatively positioned between the said sides 26 on the ways 21, and the ways 21 are in turn positioned between the adjoining faces of the said sides 26 and the carriage 2, the table 23 is secured 50 to the top portion of the said carriage 2, the motor 3 is secured to the inner-lower por-

tion of the carriage 2 and the pulley 7 is operatively secured thereon. The shaft 16 is secured to the inner portion of the said carriage 2 at right angles to the ways 21 60 adjacent to the motor 3, the arms 11 are operatively positioned on the shaft 16 and are integral with the bearing 10, the arm 17 is secured to the bearing 10 on the opposite side from the said arms 11, the clamp 30 is integral with the arms 17 and passes operatively through the inner-end portion of the said carriage 2. The shaft 27 is held operatively in the said bearing 10, the pulley 8 is secured to one end of the shaft 27, and the belt 9 is operatively positioned 65 between the said pulleys 8 and 7, the saw 12 is in turn secured to the opposite end of the said shaft 27 and passes operatively through the table 23, and the central-end portions of the shaft 27 are formed with sockets 28 and 29 respectively. The table 31 is secured to the side of the carriage 2, and the table 14 is adjustably mounted opposite the said table 31 at positions to admit the cutter head 13 therebetween, and the head 13 is in turn secured in the socket 29, and the wedges 4 are positioned under the said table 14 and secured to the side portion of the carriage 2. The wheel 18, 70 drill 19, center 33, or other tools not shown, may be secured in the said socket 29 to perform their respective operations, suitable supports not shown, may be employed with the said wheel 18, drill 19, or other tools, and the lathe 15 may be used in connection with the said center 33 by being secured to the side portion of the said bed 1. The table 36 is secured on the top-end portion of the bed 1, opposite the said sides 26, the standard 24 is secured to the outer edge of the table 36 opposite the carriage 2, and the table 25 is in turn secured to the standard 24. The guides 5, 6, 22, 34, and 37 are secured at any required angles on the tables 75 25, 31—14, 36, and 39 respectively. The drill 20 may be secured to the socket 28 over the feed 32, and the said feed 32 is in turn operatively secured to the sides 26, and the drill 19 may also be secured to the 80 socket 29 over the table 39. The pin 35 is passed through the top-inner end of the said table 23, and is secured to the table 25 when the carriage 2 is moved forward for a stationary position, as shown in dotted lines 85 100 in Figure 1.

In the operation of the combination car-

pentor machine the shaft 27 is driven in the bearing 10 by the motor 3, through the pulley 7, belt 9 and pulley 8, respectively, the said bearing 10 swings up or down on the arms 11, around the shaft 16, by being raised or lowered by the arm 17, and is then held in its raised or lowered position by the clamp 30.

10 The carriage 2 may be shifted backward and forward, or held stationary on the ways 21 between the sides 26, the carriage 2 is held in a forward position by locking the pin 40 therein to the sides 26, and may also be held in a backward position by locking the pin 35 through the table 23 into the table 25.

20 When it is desired to use the saw 12 for rip cutting, the guide 34 is secured at the correct angle, and the table 23 is secured in a stationary forward position by the pin 40, and the work is then pushed through the saw 12 for straight or bevel cuts. When the saw 12 is intended to be used for cross cut operations, the carriage 2 is allowed to 25 shift free on the ways 21 between the sides 26, and the work is cut to the angle of the guides 22 or 5, when said saw 12 is being held in a lowered, or raised position, respectively. When it is intended to cut 30 grooves, the said saw 12 is adjusted to project the required distance through the table 23, and is secured into position by the clamp 30, so as to cut the required depth into the work. When it is desired to plane work, the 35 head 13 is secured to the socket 29, the table 14 is adjusted to the elevation below the top edges of the head 13 and table 31, by the wedges 4, to provide a heavy or light cut by the head 13, as the work is being fed therethrough. When it is desired to use the 40 wheel 18, drills 19 and 20, center 33 with lathe 15, or other similar tools, a grinding or facing, boring, or turning operation is accomplished, in respective order.

45 Having thus described my invention what I claim is:

1. A woodworking machine of the class 50 described, comprising a stationary lower portion, and a carriage slidably positioned in the upper portion thereof, adapted to be set into a stationary position, in combination with a power generating and transmission means positioned in the said carriage, a driven shaft operatively connected to the 55 said power transmission means, adapted to be secured in a raised or lowered position, a holding means in connection with the end portions of the said driven shaft, a table secured on the top portion of the said car-

riage, a table secured to the lower end of 60 the said stationary lower portion of the machine, a table, adapted to be positioned over the second mentioned table, in a line with the first mentioned table, adjustable guides, adapted to be secured to the said tables, 65 cutting tools, adapted to be secured to the said holding means, as set forth.

2. A woodworking machine of the class described, comprising a stationary bed portion, a carriage operatively positioned in 70 the upper-end portion of the said bed, a power transmission means positioned in the said carriage, a driven shaft operatively connected to the said power transmission means, adapted to be secured in a raised 75 or lowered position, a holding means in connection with the end portions of the said driven shaft, a table secured on the top portion of the said carriage, a table secured at one end portion of the said stationary 80 bed, a table positioned over the second mentioned table in a line with the first mentioned table, adapted to be disconnected from the machine, or secured to the said carriage, an adjustable table, adapted to be 85 secured to the side portion of the said machine in relation to one of the said holding means, adjustable guides, adapted to be secured to the said tables, cutting tools, adapted to be secured to the said holding 90 means, as set forth.

3. A woodworking machine of the class described, comprising a stationary bed portion, a carriage operatively positioned in the upper-end portion of the said bed, a power 95 transmission means positioned in the said carriage, a driven shaft operatively connected to the said power transmission means, adapted to be secured in a raised or lowered position, a holding means in connection with the 100 end portions of the said driven shaft, a table secured on the top portion of the said carriage, a table secured to the lower-end portion of the said stationary bed, a table positioned over the second mentioned table in a line with the first mentioned table, adapted to be removed from the said machine, or secured to the said carriage, a lathe bed, adapted to be secured to the side portion of the said machine in relation to 105 one of the said holding means, adjustable guides, adapted to be secured to the said tables and lathe bed, machine tools, adapted to be secured to the said holding means, as set forth.

In testimony whereof I affix my signature.

LOUIS F. RUZIECKI.
